FILING SHELF

Preston Nagelkirk, Zeeland, Mich., assignor to Herman Miller, Inc., Zeeland, Mich., a corporation of Michigan

Filed Nov. 16, 1961, Ser. No. 67,560

Term of patent 14 years

(Cl. D74—9)

FIG. 1

FIG. 2

FIG. 3

FIG. 1 is a perspective view of the filing shelf of this invention;

FIG. 2 is an end elevational view of the filing shelf of this invention; and

FIG. 3 is a rear view of the filing shelf of this invention.

The end of the filing shelf opposite that shown in FIG. 2 is the mirror image of FIG. 2.

The design is characterized by the specific interconnecting cross wire supports in association with the paired shelf members all as shown.

I claim:

The ornamental design for a filing shelf, substantially as shown and described.
